FURNACE WALL CONSTRUCTION

Filed March 4, 1950

UNITED STATES PATENT OFFICE

2,669,115

FURNACE WALL CONSTRUCTION

William A. Waite, Saunderstown, R. I.

Application March 4, 1950; Serial No. 147,669

3 Claims. (Cl. 72—102)

1

This invention relates to a furnace wall construction and has particular reference to the construction of the face of the wall which is to be contacted by the heat and the tying and supporting of such face portion into the wall construction.

Reference is made to my prior Patent 2,212,412, dated August 20, 1940, which explains certain difficulties which are present in the prior art and one of the objects of this invention is to attain the desired objects of said patent and, at the same time, improve upon the construction shown therein by strengthening the wall structure and by increasing the efficiency of the lock between the heat contacted section and the supporting section next adjacent thereto.

Another object of the invention is to provide a division of the heat contacted surface into panels, separated by horizontal and vertical expansion joints, each self supporting.

Another object of the invention is to simplify the wall construction and in its simplest construction require fewer special shapes and of such shapes as are required to use a simpler design than that shown in my above-mentioned patent.

Reference is also made to my co-pending application, Serial No. 701,451, filed October 5, 1946, now abandoned, which shows a new form of header brick having a V-shaped surface and also a new form of locking brick of a generally trapezoidal form; and one of the objects of this invention is to utilize in other locations the V-shaped header which occurred only as a base in the above-mentioned application and to utilize this V-shaped header as a lock, as well as to provide an arrangement whereby an expansion joint of a self-clearing type such as shown in my prior Patent 2,212,412, thus obtaining these several advantages from this additional use of this V-shaped header.

Another object of this invention is to provide a wall construction which will have in its simplest form fewer special shapes than shown in my above-mentioned application.

Another object of this invention is to provide a stronger wall construction than that shown in my above-mentioned application.

Another object of this invention is to provide a removable unit in the heat contacted section which will enable a more simple repair or replacement of ruptured bricks in the heat contacted face should such rupture occur.

With these and other objects in view, the invention consists of certain novel features of con-

2

struction, as will be more fully described and particularly pointed out in the appended claims.

In the accompanying drawings:

Figure 1 is a sectional view of a wall of simplified construction made in accordance with this invention;

Figure 2 is a face view of this furnace wall;

Figure 3 shows a sub-section of the heat contacted face of generally L-shaped structure;

Figure 4 is a perspective view of a notched header of special construction;

Figure 5 is a perspective view of the locking tie of special construction;

Figure 6 is a perspective view of a locking brick of the face which is of special construction;

Figure 7 is a parallelepiped stretcher brick of special construction;

Figure 8 is a sectional view of a wall embodying fundamentally the construction of Figure 1 but modified with respect thereto by having additional specially constructed units therein;

Figure 9 is a face view of the structure shown in Figure 8;

Figure 10 is a perspective view of a header of parallelepiped form and is special for the structure of Figure 8;

Figure 11 is a perspective view of one of the locking ties and is additionally special for the structure of Figure 8 to match up with the structure of Figure 10; and

Figure 12 is a perspective view of a rectilinear brick of common structure utilized in the wall particularly on the cold face of the wall;

In proceeding with this invention, I provide a heat contacted section and a supporting section adjacent to this heat contacted section with units sometimes referred to as bricks, tying the two sections together. The heat contacted section comprises bricks largely of special shape which, in the simplest form of construction, is reduced to but four special shapes, and I so arrange the construction as to provide for expansion vertically of the wall by a joint or space which will be at such an angle as to discharge any foreign matter which may be likely to become lodged therein, and I so arrange the special shapes that they are tied together and to the supporting section by dove-tailed locks which will serve to transfer the weight of the heat contacted section inwardly through a tie to the adjacent supporting section, and I further provide generally vertical spaces for horizontal expansion thus forming panels or sub-sections of the plurality of bricks in the heat contacted section which may be removed and replaced, should

any of the bricks therein become melted or otherwise injured by the excessive heat without taking down the panel portion above the damaged face of the wall.

With reference to the drawings, and particularly the simplified form shown in Figures 1 and 2, the heat contacted section is designated 15 and includes all of the bricks, having an end, which are exposed in the face 16, which is the face shown in Figure 2. The bricks in this heat contacted section include three special shapes and the regular right angularly shaped brick of common form. The arrangement is such that there are a plurality of sub-sections designated generally 17 and shown in Figure 3, which are superimposed one upon the other.

The sub-section 17 comprises upper brick 18, shown in perspective in Figure 6, which is of a trapezoidal form on its end faces 19 comprising a heat exposed face 20 of rectangular form and an opposite face 21 of rectangular form of larger size; likewise, the bottom is of rectangular form, while its top 23 is also rectangular but is sloping from the face 20 to the face 21. This brick serves as a locking unit in the arrangement used.

Beneath this brick 18 there is a brick 24 of regular construction, right angular at all corners, and shown in perspective in Figure 12. Below this brick 24 there is another brick 18 which has its inclined surface downwardly instead of upwardly, as illustrated above the brick 24. Below this second brick 18 there are two stretcher bricks 25 of parallelepiped form and shown in perspective in Figure 7, in which the heat contacted exposed face 26 is rectangular and the opposite side 27 is also rectangular. Likewise, the top 28 and bottom 29 are rectangular, but the ends 30 are each parallelograms, with two acute angles and two obtuse angles.

Beneath this parallelepiped brick there is an upper header 31, shown in perspective in Figure 4. This shape is in effect double the structure 18, shown in Figure 6, and has sides 32 of double trapezoidal form providing a V-shaped surface 33, while its opposite face 34 and the heat contacted faces 35 and inner face 36 are each of rectangular form. This V-notched header serves as a base of the sub-section 17 to provide an L-shaped construction of a cantilever type with portions of the surface on one side of the apex of the V surface extending onto the outer brick section. I may also consider the rectangular header 31 of usual form which is located beneath this V-shaped header 31 and also another V-notched lower header 31' in inverted relation to the header 31 as a part of this sub-section with portions of the surface on one side of the apex of the V surface extending onto the outer brick section. The header 31' serves as a lock with its outer inclined surface serving as one face of the horizontal expansion joint designated 40 for vertical expansion and provided between this inverted V-shaped header 31' and the locking brick 18 next adjacent it. A vertical joint for horizontal expansion 40' is provided for dividing the heat contacted surface into panels each self-supporting. These expansion joints 40, 40' are shown by heavy lines rather than attempting to show a space by two lines which might be so close together as to be obscure.

This L-shaped sub-section structure 17 is duplicated throughout the heat contacted face of the wall and is tied into the supporting section designated generally 43 by a special shaped brick 44, shown in perspective in Figure 5, and comprising

a side 45 essentially of a trapezoid extended by a rectangle; thus, there is a horizontal portion 46 and inclined portion 47 rising therefrom to provide opposite rectangular ends 48 and 49 of different sizes. This inclination 47 contacts one-half of the V-shaped surface of the header 31 or 31' to provide a dovetail type lock and is of a shape to fit and tie in the supporting section adjacent thereof, or it may be considered that the two V-notched headers which form the base of the L unit provide a dovetail lock with two of the bricks 44 so as to hold the L-shaped unit in place. The inclination of the V-shaped base header on the outer half thereof and the parallelepiped stretchers above it and lock 48 are of such inclination as to transfer the weight of the sub-section inwardly through the base header and the lock which is associated therewith to the supporting wall, thus the weight of each sub-section is successively transferred inwardly into the supporting section, while at the upper end of each said sub-section, there is left an expansion joint which being on an incline downwardly from the face 16 will cause discharge of any foreign matter which might tend to get into the joint and limit expansion. This expansion joint also indicates clearly that the weight of each sub-section is transferred inwardly to the supporting section and is not transferred to the sub-section below it.

In some cases the sub-section such as shown at 17 may have interposed in it a header 50, as shown in Figure 8 and shown in perspective in Figure 10, which is of parallelepiped form, having twice the height of and twice the extent from the heat contacted face as the parallelepiped stretcher 25. In this case, the V-shaped header 31 which forms the base has three parallelepipeds 25 between it and the header 50, while two locking bricks 18 and a regular brick 24 are located above the header 50 and between it and the V-shaped locking header 31' above it. The expansion joint will be at 40, the same as previously described.

In the modified construction of Figures 8 and 9, in order to match up with the header 50, I provide a tying lock 51, shown in perspective in Figure 11, which will have an inclined surface 52 causing a tapered end from the generally rectangular structure of one-half of this unit, and this structure 51 will be positioned so that the inclined surface 52 will engage one-half of the header 50 that the generally rectangular structure may be built out and the rectangular brick supporting wall adjacent to the heat contacted section may be tied in.

By this arrangement an expansion joint is provided for both of the walls and a dove-tail lock is provided between the heat contacted section and the supporting section adjacent thereto by reason of the tying bricks which have faces to contact either the V-shaped header or the parallelepiped header so that a very strong lock or tie between the heat contacted section and the adjacent supporting section is provided. Likewise, the structure is so formed that an L-shaped cantilever sub-section having a much increased cross section is formed for easy removal and replacement and for transferring the weight from the heat contacted section to the inner supporting section step by step as the L-shaped unit is vertically multiplied along the heat contacted face.

I claim:

1. In a furnace wall construction, an outer brick section and an inner brick lining having a

heat contacted face, said lining having a plurality of vertically arranged sub-sections each comprising upper and lower header bricks of equal size and shape having oppositely inclined plane surfaces converging toward each other in generally a V-shape with the V surface of an upper header upwardly facing and the V surface of the lower header downwardly facing, and with the portion of said headers on one side of the apex of the V surface extending into the outer brick section, the inclined face of the upper header of one subsection and the inclined face of the lower header of the next subsection providing a dove-tailed space and a plurality of bricks in the outer brick section presenting a dove-tail lock extending into said dovetail space and contacting said inclined faces to lock the sub-sections and outer brick sections together and to support the subsection on the outer section.

2. In a furnace wall construction, an outer brick section and an inner brick lining having a heat contacted face, said lining having a plurality of vertically arranged sub-sections each comprising upper and lower header bricks of equal size and shape having oppositely inclined plane surfaces converging toward each other in generally a V-shape with the V surface of an upper header upwardly facing and the V surface of the lower header downwardly facing, and with the portion of said headers on one side of the apex of the V surface extending into the outer brick section, the inclined face of the upper

header of one subsection and the inclined face of the lower header of the next subsection providing a dove-tailed space and a plurality of bricks in the outer brick section presenting a dove-tail lock extending into said dovetail space and contacting said inclined faces to lock the sub-sections and outer brick sections together and to support the subsection on the outer section, said subsection also comprising a plurality of stretcher bricks contacting the upper header surface on the side of the apex of the V surface toward the heat contacted face and spaced from the V surface lower header of the subsection above it to provide for expansion.

15 3. In a furnace wall as in claim 2 wherein the stretcher bricks present upper and lower inclined surfaces in generally dove-tail shape to conform to the surfaces of the upper header contacted surface of one subsection and the lower header

20 inclined surface of the subsection above it.
